EXHAUST PURIFIER

Stefan Schneider, Philadelphia, Pa.

Application July 30, 1932. Serial No. 626,527

4 Claims. (Cl. 183—17)

My invention relates to new and useful improvements in an exhaust purifier and has for one of its objects to provide a simple and effective means for connection with the exhaust of an 5 internal combustion engine or the like to purify the exhaust products and eliminate the dangerous or sickening constituents thereof before being projected into the atmosphere.

Another object of the invention is the provision of a casing having two compartments in communication through a restricted passageway or nozzle leading from the primary compartment to a location intermediate the ends of the secondary compartment near the bottom thereof.

Another object of this invention is to position a filtering or screening means in the primary compartment so as to be disposed across the path of flow of the products of combustion through the device and to provide a liquid purifying chemical 20 in the secondary compartment which will cover the outlet end of the nozzle or communicating passageway between the two compartments.

A further object of the invention is to include a chemical purifier as a part of the filtering or screening element if desired.

A still further object of the invention is to provide a screening or filtering element consisting of a porous, compressible material, such as a sponge, and more particularly a metal sponge 30 or a bunch of strands of metal or other fibres slidably mounted in the primary compartment and spring pressed in one direction.

With these and other ends in view, this invention consists in the details of construction and combination of elements hereinafter set forth and then specifically designated by the claims.

In order that those skilled in the art to which this invention appertains may understand how to make and use the same, I will describe its construction in details, referring by numerals to the accompanying drawing forming a part of this application, in which:—

Fig. 1 is a top plan view, partly in section, 45 of the exhaust purifier as contemplated by my invention.

Fig. 2 is a longitudinal section thereof on the line 2—2 of Fig. 1.

In carrying out my invention as herein embodied, 50 5 represents the exhaust purifier casing including two members or units 6 and 7 of substantially oval shape joined together end to end to provide a unitary structure.

Both of the members are hollow and form 55 compartments, the one in member 6 being termed

the primary compartment 8 while the other will be known as the secondary compartment 9.

The member 6 has an externally threaded nipple 10 at one end and an internally threaded socket 11 at the opposite end as well as an access opening 12 at one side when considered with relation to the position in which the device is mounted when in use. The access opening is normally closed by a cap or closure plate 13 held in place by suitable fastening devices 14, such as 60 stud bolts, and a gasket 15 may be used to provide a tight joint.

The member 7 has an externally threaded nipple 16 at one end to be screwed into the socket 11 for connecting the members together and forming the casing 5. At the other end of member 7 is an outlet 17 and this end of said member 65 may be formed into a spout 18.

In the side of the member 7 is a filling opening 19 normally closed by a screw plug 20 and in the bottom of the same member is a drain opening 21 and like the filling opening is normally closed by a screw plug 22.

At the inner or nipple end of the member 7 is formed an internal nozzle 23 having its outlet end 70 terminating intermediate the ends of the said member 7 near the bottom thereof and provides a communication passageway 24 from the primary compartment 8 to a point a considerable distance inside of the compartment 9 close to the bottom.

The nozzle is preferably of curved formation and its outlet end is submerged in a liquid purifying chemical 25 contained within the secondary compartment 9 in the member 7.

In order to prevent undue splashing and spilling of the liquid chemical, a suitable baffle plate or fin 26 is formed in the outlet 17 and the space between said baffle plate and the lower part of the spout 18 is formed an end wall 27.

Disposed across the inlet end of the nozzle or positioned between the two members across the communicating passageway is a screen 28 to prevent particles of material, such as rust, carbon or soot entering the secondary compartment 9.

The member 6 has a compressible porous filtering element 29 disposed within the same across the primary compartment 8 or at right angles to the longitudinal center of the member 6 and snugly fits the walls of said member to become a barrier to certain constituents of the products of combustion of an explosive engine or the like.

The filtering element 29 is slidable lengthwise of the member 6, but is normally held in a position approximately midway between the ends of 110

the primary compartment by a helical spring 30.

As above stated, said filtering element is compressible and porous, therefore it is preferably formed from spongy material and also it is further preferred that it be a metal sponge, although I have found a bunch of metal strands or fibres can be utilized.

If found desirable, the filtering element 29 may contain a purifying chemical.

- 10 In operation the nipple 10 is connected in any suitable manner to the exhaust of an explosive engine. As the products of combustion are expelled they enter the forward part of the primary compartment 8 and contact the filtering element 29. The products of combustion being under pressure will compress the filtering element and close the pores thereof. This will provide an almost, if not complete, barrier for the products of combustion causing solid particles to drop to the 20 bottom of the primary compartment.

As soon as the initial force of the expelled products of combustion is dissipated, the filtering element will expand and permit the gases to flow through the filtering element and thence through the screen 28 where any particles which happen to pass through the filtering element will be arrested and caused to drop into the bottom of the primary compartment although in back of the filtering element.

- 30 The gases will flow through the nozzle 23 to the bottom of the liquid chemical 25 through which said gases will float to the top entering the empty space of the secondary compartment 9 in a purified and harmless state, finally passing through 35 the outlet into the atmosphere.

By making the walls of the member 6 or more particularly the inner surfaces thereof tapering, as shown, as the filtering element 29 is moved against the action of the spring, said filtering element will be compressed radially thus more effectually closing the pores thereof.

During use of the device, the filtering element will reciprocate at considerable speed and the pores thereof will be closed and opened at each 45 explosion of the engine.

The primary compartment 8 may be cleaned or the parts therein replaced upon removal of the closure plate 13 while the secondary compartment may be drained or the liquid chemical 50 replenished by simply removing the screw plugs 22 and 20 respectively.

Of course I do not wish to be limited to the exact details of construction herein illustrated as these may be varied within the limits of the appended claims without departing from the spirit 55 of my invention.

Having thus fully described my invention, what I claim as new and useful is:—

- 60 1. In combination, an oval casing member pro-

viding a primary compartment with tapering walls and having an access opening in one side, a closure plate for said opening, a nipple at one end for connection to an engine exhaust, a socket at the opposite end of said member, a second oval casing member providing a secondary compartment and having a filling opening in one side and a drain opening in the bottom, removable means to close said openings, a nipple at one end of said second member for insertion in the socket of the first member to connect said members together and having an outlet at the other end, a nozzle formed with the nipple end of the second member and projecting to a point intermediate the ends of said second member near the bottom thereof to form a communicating passageway between the two compartments, a liquid chemical in the secondary compartment in which the outlet end of the nozzle is submerged, a screen disposed across the inlet end of said nozzle, a metal sponge slidably mounted in the primary compartment and disposed across the same, and a spring to normally force said sponge away from the inlet end of the nozzle.

2. The structure in claim 1, in combination 100 with a baffle in the outlet of the second member, and a chemical carried by the sponge.

3. An exhaust purifier including a casing for the passage of products of combustion from an explosive engine, said casing having a tapered 105 inner portion opposite an inlet for said products of combustion, a porous filtering element disposed across the interior of said casing and forced into the tapered portion by the action of said products of combustion whereby said filtering element will be compressed laterally and longitudinally, and a spring located in said casing and coacting with the filtering element to move the latter in the direction opposite to that in which it is moved by the products of combustion 110 to permit said filtering element to expand to its normal condition.

4. An exhaust purifier including a casing having an inlet at one end and an outlet at the opposite end, the outlet end of said casing being 120 interiorly tapered whereby the smaller part of the tapered portion is at the outlet, a compressible porous filtering member mounted in the casing for movement toward and away from the outlet, said filtering element being moved toward the 125 outlet by the pressure of the products of combustion entering the casing and causing it to be compressed longitudinally and laterally as it is forced toward the smaller part of the tapered portion of the casing, and means to move said 130 filtering element toward the larger part of the tapered portion whereby it is free to expand to its normal condition.
